DESIGN FOR A HAT

Aaron Rothchild, New York, N. Y.

Application September 17, 1940, Serial No. 95,134

Term of patent 3½ years

To all whom it may concern:

Be it known that I, Aaron Rothchild, a citizen of the United States, residing at New York city, in the county of the Bronx and State of New York, have invented a new, original, and ornamental Design for a Hat, of which the following is a specification, reference being had to the accompanying drawing, forming part thereof.

Fig. 1 is a perspective view of a hat, showing my new design.

Figs. 2, 3, and 4 are fragmentary views, to an enlarged scale, showing the top, the edge, and the bottom of the brim respectively.

The characteristic feature of the design resides in the serrated brim edge of the hat having inserts as indicated in full lines on the drawing.

I claim:

The ornamental design for a hat, substantially as shown and described.

AARON ROTHCHILD.
